DISPLAY BOX

Ralph M. Somerfield, New York, N.Y., assignor to Gruen Industries, Inc., New York, N.Y., a corporation of Ohio

Filed July 24, 1959, Ser. No. 56,932

Term of patent 7 years

(Cl. D58—12.7)

Figure 1 is a perspective view of a display box showing my new design with the box being in opened condition.

I claim:

The ornamental design for a display box, substantially as shown.
